[57] **CLAIM**

The ornamental design for a combined computer mouse pad and hand rest, as shown and described.

DESCRIPTION

FIG. 1 is a perspective view;

FIG. 2 is a left side view;

FIG. 3 is a right side view;

FIG. 4 is a top plan view;

FIG. 5 is a front view;

FIG. 6 is a rear view;

FIG. 7 is a bottom plan view;

FIG. 8 is a left view, the claimed design is shown in expanded position;

FIG. 9 is a perspective view of a second embodiment;

FIG. 10 is a left side view;

FIG. 11 is a right side view;

FIG. 12 is a top plan view;

FIG. 13 is a front view;

FIG. 14 is a rear view;

FIG. 15 is a bottom plan view; and,

FIG. 16 is a side view in elevated position, the broken line drawing of a keyboard is for illustrative purposes only and forms no part of the claimed design.

The broken line drawings of a hand, a computer mouse, and a keyboard in FIGS. 3, 8 and 11 are for illustrative purposes only and form no part of the claimed design.
